UNITED STATES PATENT OFFICE

2,005,213

EXTENSION SLIDE DEVICE

Max Wurm, Brooklyn, N. Y.

Application September 1, 1934, Serial No. 742,376

3 Claims. (Cl. 311—69)

My invention is related to extension slide mechanism which is adapted for use with ordinary extension tables in which one or more table top-members are slid back and forth in the horizontal, and also for use with a shelf or horizontal ledge. Some of the important features of the invention are, that simplicity of construction is obtained; that the peculiar construction and arrangement of the guide fixtures maintain the sliding members parallel and retain them against vertical movement so that they keep the same level; that the guide fixtures also serve as gaging means for setting and positioning the fixtures parallel and in alinement; that outwardly projecting stops may be conveniently provided at the respective ends of the sliding-members; that the device may be made entirely of metal or partly of metal and partly of wood, and the metal parts made from angle or channel-irons; that it may be manufactured at relatively low cost, and that its structure and arrangement is such that the manufacturer need only produce and keep in stock about three different sizes and will be able to extend such sizes to any desired extension by merely moving a guide-fixture to the right or left in order to increase or decrease the extension of the slides. Other advantages of my improved slide device will be understood from the detailed description hereinafter given in connection with the drawing herein.

I have illustrated types of my invention in the accompanying drawing, wherein;

Figure 1 shows a top plan view of an extension table embodying my improvements, the form of the slide being of the equalizing kind, and only one longitudinal half of the table being shown.

Figure 2 shows an enlarged vertical sectional view of the structure shown in Fig. 1, the plane of the section being indicated by the broken-line 40 2—2, in Fig. 1.

Figure 3 shows an enlarged vertical cross-sectional view of the structure shown in Fig. 2 the plane of the section being indicated by the broken-line 3—3, in Fig. 2.

Figures 4, 5 and 6 show cross-sectional views similar to Fig. 3, but of different modifications of the three membered slide.

Referring to the drawing, in which like numerals of reference designate like parts throughout, and considering the structure shown in Figs. 1, 2 and 3, 1 and 2 indicate two cooperating table top members which are adjustable toward and away from each other horizontally to vary the length of the table in the usual way. In this form, my device consists in three juxtaposed

members 3, 4 and 5, having relative sliding movements longitudinally in the horizontal. The central-member 4 is fixed upon a subjacent support, such as an ordinary bridge or stretcher or other suitable part, which is not here shown, and it serves as a guide and support for the two associated side-members 3 and 5, which are mounted to slide upon the opposite sides of the central-member; the member or section 3 being secured by screws 6 to the underside of the top-member 10 2, and the member or section 5 being secured by screws 7 to the underside of top member 1.

The side-members 3 and 5 are constructed and operate alike so that a description of one will serve for both, the same reference numeral being used for member 3 but with a prime mark thereon. The member 5 is a channel-iron with a flat back 8 sliding along the side of the central-member 4 with its upper right-angled flange 9 attached to the underside of top-member 1 by 20 screws 7. The lower flange 10 of member 5 is narrower than the upper flange and forms a guide-rib which slides back and forth in guide-ways or grooves 11 and 12 formed in the fixtures or brackets 13 and 14, respectively, which are secured by screws 15 and 16, respectively, to the side of the central-member 4, as indicated in Figs. 2 and 3.

The fixtures 13 and 14 are spaced apart a certain distance and the latter is engaged by a fixed 30 stop 17 which is formed at the inner end of side member 5 by a bent extension of the guide-rib 10, and the fixture 13 is engaged by an outwardly projecting stop 18, which is struck up from the back portion 8 of the member 5, as shown in Fig. 35 2. These stops, by engaging or colliding with the sides of the respective fixtures, act to limit the range of relative longitudinal movement of the sliding member 5; the stops being formed integral with said member.

The fixtures or brackets 13 and 14 may be formed from suitable sheet-metal, likewise the side-members 3 and 5, and they are so shaped as to pass upwardly around the guide-rib 10 of sliding member 5 with the upwardly extending flat 45 part engaging the side of said member to provide a suitable guiding means for the same, and the fixtures serve to prevent vertical movement of the sliding side-members and keep them on the same level, and also act to prevent lateral or 50 wobbling movement of said members.

An important feature of the guide-fixtures is the provision of positioning-means therefor, which consists of an inwardly projecting flange 19 on fixture 14 taking into a horizontal slot or 55

- cut 20 formed in the side of central-member 4, and a similar flange 21 on fixture 13 taking into a slot 22 in the side of member 4, the slots 20 and 22 being in horizontal alinement. By means of 5 this simple construction, the guide way fixtures may be mounted in their true positions with certainty of parallelism and alinement on the central member, so that the parts may be assembled quickly without necessitating the taking of measurements in order to get the fixtures in their proper places, since they are practically duplicates and the positioning-flange and guide way of each are the same distance apart vertically. If preferred, in all of the forms, the two fixtures 10 or brackets 13 and 14, may be merged into one long bracket covering the horizontal distance of the two separate brackets, the rectilinear movements of the sliding members being the same in each form.
- 20 In the form shown in Figs. 1, 2 and 3, the device is constructed with equalizing means comprising a rack 23 formed in the back of side-member 5 and a similar rack 23' formed in side-member 3, with an intermeshing cog-wheel 24 turning on a vertical pivot 25 on the upper face of the central member 4, so that the slides move longitudinally and simultaneously in opposite directions the same distance, in a manner well known. The bracket 14 has its upper edge cut-away at 26, 15 to clear the teeth of the cog-wheel.
- 30 In the modified form shown in Fig. 4, which may be of the equalizing type or not, the structure is the same as that shown in Figs. 1 to 3, with the difference that instead of having the gage flange 19 thereof forced into a slot in the central member, this flange 19^a of bracket 14^a takes under the lower edge of central-member 4^a and a screw 16^a secures the bracket to the member.
- 40 In the modified form shown in Fig. 5, the sliding side-member 5^b is like that of the previously described forms, but its cooperating bracket or fixture 14^b is bent back on itself in a U-shape, the inner limb being carried up above the central-member 4^b with the positioning-flange 19^b extending over the top edge thereof, and the outer limb forming a groove 12^b to guide the lower edge of the sliding member 5^b, as previously described.
- 45 In the modification shown in Fig. 6, the construction is the same as that of Figs. 1 to 3, the sliding side-member 5^c cooperating with the fix-

ture 14^c in the same way, but the gage-flange at the foot of the fixture is omitted and a gage screw 16^c is used to secure the fixture to the side of central-member 4^c.

Having thus described my invention, what I claim and desire to secure by Letters Patent is:—

1. An extension slide device comprising a unit of three juxtaposed members having relative longitudinal sliding movement, the central one of which serves as a fixed guide-member for each of the engaging sliding side-members and the latter being provided with outwardly extending guide-ribs, guide-fixtures provided with inwardly disposed guide-ways engaged by said guide-ribs, said fixtures being mounted on said central member below and exteriorly of said side-members and serving to guide the side members in parallel longitudinal movement and in the same horizontal plane.

2. An extension slide device comprising a unit of three juxtaposed members having relative longitudinal sliding movement, the central one of which serves as a fixed guide-member for each of the sliding side members and the latter being provided with outwardly extending guide-ribs, 25 guide-fixtures provided with inwardly disposed guide-ways engaged by said guide-ribs, said fixtures being mounted on said central member below and exteriorly of said side-members and serving to guide the side-members in parallel longitudinal movement, and means on the lower part of each fixture adapted to engage said central-member and serving as positioning means to set the guide-way of each fixture in horizontal alinement on said central member.

3. An extension slide device comprising a unit of three juxtaposed members having relative longitudinal sliding movements, the central one of which serves as a fixed guide member for each of the sliding side members, each side member 40 consisting of a channel-iron having outwardly extending flanges with its back opposite to and in sliding relation with said central member and with its lower flange serving as a guide-rib, one or more brackets or fixtures mounted upon each side of said central member and provided with guide grooves or ways for receiving the guide-ribs of said side members, and the upper flange of each said channel-iron serving as an attaching part to the under side of a table top member. 45
